UNITED STATES PATENT OFFICE

WILLIAM D. MURRAY, OF NORFOLK, VIRGINIA.

OIL-BURNER.

Specification of Letters Patent. Patented July 5, 1921.

1,883,329.

Application filed April 1, 1919. Serial No. 933,713.

To all whom it may concern:

Be it known that I, WILLIAM D. MURRAY, a citizen of the United States, residing at Norfolk, in the county of Norfolk and State 5 of Virginia, have invented new and useful Improvements in Oil-Burners, of which the following is a specification.

This invention relates to gaseous fuel burners of that type in which a fuel oil, 10 such as for example kerosene, is converted into gas or vapor and burned.

In the particular embodiment of the invention herein illustrated and described, I have shown this burner as adapted to the heating of furnaces, stoves and the like, although it will be understood that its use is not confined to the particular disclosure herein made.

Broadly considered this general type of burner is old, it having been proposed heretofore in the art to convert liquid fuel into vapor, commingle that vapor with air and burn the resultant mixture for heating purposes. I do not therefore claim to be the 25 inventor of the broad concept, nor do I claim to be the first to produce a burner capable of carrying into effect this method of utilizing liquid fuel and the vapors generated therefrom. The burner which I have invented however, possesses certain novel features and advantages over those now known to me, particularly with respect to the features of air delivery, with respect to ease of installation and replacement, and with 30 respect to adaptation of the burner to fire pots of varying sizes, and it is to these distinguishing characteristics that my claims, appended to this description, are directed.

In order that the invention may be clear 40 to those skilled in the art, I have illustrated one embodiment thereof in the accompanying drawings, but it will be understood that this disclosure is illustrative and in no sense restrictive, and that such variations from 45 the structure as are within the range of mechanical skill, are to be regarded as within the purview of my invention.

In the drawings—

Figure 1 is a longitudinal sectional view 50 vertically of the burner.

Fig. 2 is a plan view of the supporting plate, oil pan and burner.

Fig. 3 is a plan view of the draft and air delivery tubes nested.

Fig. 4 is a bottom view of the draft tubes 60 as shown in Fig. 3.

Fig. 5 is a detail plan view of the bed plate provided with adjustable edge plates to adapt the device to fire pots of varying sizes.

Fig. 6 is a sectional view on substantially the line 6—6 of Fig. 5.

Fig. 7 is a view in plan of a burner designed for rectangular fire pots.

Fig. 8 is a longitudinal vertical section 65 of the view shown in Fig. 7.

Fig. 9 is a view in plan of the side and end extension plates for this form of burner.

Fig. 10 is an edge view of an end extension plate.

Fig. 11 is a sectional view on substantially the line 11—11 of Fig. 2.

Fig. 12 is an enlarged view of the pan, the distributing plate and a portion of one of the supporting units.

Referring to the drawings by numbers, like numbers indicating like parts in the several views, 10 indicates a bed plate unit of which there may be as many as are desirable, four being shown in the present instance, and since, in this disclosure, the burner is adapted for circular fire pots, the units 10 are of segmental form, their meeting edges being provided with abutting grooves 11 undercut to receive fire clay 12 which maintain the segments in even and proper relation to one another when assembled, and having also a depending vertical web 13 and an outstanding peripheral web 14. Each of the said units 10 is provided with a draft opening 15, one opening to each unit being shown in the present disclosure, although it will be understood that a unit might have more than one draft opening or the units might be provided alternately with draft openings, or any other arrangement which the needs of the case demanded. The draft openings 15 are surrounded by a vertical ledge or wall 16, and at their inner ends 100 are provided with horizontally disposed ledges 17 to form receiving and supporting seats for draft tubes 18.

The draft tubes 18 as shown, are of

curved form and are seated in the draft openings 15, as best illustrated in Fig. 1, with the inner edge of the tube resting on the ledge 17, the rear edge of the tube being provided with a lug or lip 19, which engages beneath the floor of the unit 10, as shown in Fig. 1, so as to support the draft tube 18 in position. This engagement of the tube with the bed plate unit 10 admits of the removal and insertion for cleaning, repair or replacement, without the necessity of uncoupling any of the parts and without taking down the other tubes or removing the bed plate units from the fire pot. It gives, furthermore, a very rigid closely fitting construction and preferably as at 20, the lower end of the tube 18 will be flared downwardly to give an increased area and strengthen the construction 20 against the strain on the lugs or lips 19.

The said tubes 18 at their inner ends are of such formation as to nest with the other tubes, the end formation of the tubes in the present instance being shown as triangular, 25 since there are four tubes arranged at 90° from one another successively about the burner, but such design or formation of the tube ends may, of course, be varied to suit the needs of the particular assemblage of 30 tubes. The inner ends of the tubes are provided with walls 21 which abut as shown in Fig. 4, so that while the nested ends of the tubes deliver a substantially solid column of air, the draft currents coming through the 35 tubes do not meet and comingle within the tubes or within a central chamber, as in some constructions now known to me, and the objectionable crosscurrents and back-drafts due to any inequalities of currents 40 coming through the several tubes, are entirely eliminated. This results in a steady and uniform delivery of air from the nested ends of the draft tubes.

The units 10, as stated, are of segmental 45 form, in the present disclosure, and when assembled provide an open center to receive an oil pan 22, the rim flange 22' of which engages over an upwardly projecting ledge 23 extending from the units 10 so as to lock 50 the units together. The said pan 22 has at one side, an overflow pipe 24 which will prevent any flooding and overflow of the pan upon starting the burner, the said overflow pipe 24 delivering to any suitable receptacle 55 or reservoir. Centrally of the pan 22 is an open boss 25 having in its top, a seat 26 to receive a perforated plate 27 which is preferably loosely mounted in the seat 26 so that it may be readily removed and having, as 60 shown, perforations through which air may be fed to the burner or oil head.

The burner or oil head is preferably of the form shown and comprises a concavo-convex disk 28 having on its under concave 65 side a central boss 29, through which is a

passage 30 which is threaded at its lower end and flares outwardly at its upper unthreaded end into the convex surface of the plate or disk 28. The oil feed pipe 31 passes loosely through the disk 27 and engages the threaded 70 boss 29 on the disk 28, the said feed pipe 31 being secured and held in position in any suitable manner. In order to maintain the oil distributing disk or head 28 in proper relation to the draft tubes, I preferably provide a collar or sleeve 31' loosely surrounding the oil feed pipe 31, said collar 31' resting at its lower end upon the plate 27 with its upper end abutting and sustaining the lower end of the boss 29. These collars or 80 sleeves 31' will be of proper length to maintain the oil distributor in its adjusted relation to the draft tube and will support the plate 28 and the oil tube in position.

By mounting the plate 27 loosely in the 85 boss 25 with the oil tube 31 traversing it loosely, and by reason of the manner of assembling the other elements as heretofore described, the matter of installing or taking down the burner is a simple one. The unit 90 construction of bed plate; the separable oil pan with its associated distributor parts; and the knock-down nested draft tubes provide a burner which can be readily installed in furnaces or heating stoves, through the 95 furnace or stove door without the necessity of taking down or dismantling the furnace or stove proper and for the purposes of repair and replacement, the present construction is a most convenient one. 100

In order that the burner may be fitted to fire pots of varying sizes within reasonable limits, and to take care of any slight variations in the fire pot wall, I may provide the units 10 with adjustable plates 32 conforming to the contour of the units, the plates in the present instance, conforming to the segmental shape of the units. These plates 32 will be removably and adjustably secured by means of the slots 33 and the bolts 34 so that 110 said plates may be extended or retracted with respect to the circumference of the bed plate and the burner adjusted to varying sizes of fire pots. In order to prevent any openings or crevices appearing between the edges of the plates 32 when they are expanded, I preferably lap the edges of the plates, as shown at 34, so that complete circumferential continuity of the expansible plates is 115 preserved, and no openings which would interfere with the up-draft through the fire pot are presented. 120

The action of the burner when assembled is in general, like the action of burners of this type, with this important exception, namely 125 that the up-draft from below the grate, which is stopped and directed by the covering bed plate into and through the curved draft tubes, is delivered by these draft tubes under the present construction, in a plural- 130

ity of distinct closely assembled streams at the delivery ends of the nested tubes to the distributer, and the partition walls 21 at the delivery ends of the draft tubes prevent any 5 cross-currents or objectionable eddies which are likely to be caused where the several air currents meet and comingle prior to their delivery at the delivery ends of the draft tubes.

10 In the form of the invention shown in Figs. 7 to 10 inclusive, the burner is developed for use with a rectangular fire pot and in this embodiment there is preserved the same unit type of construction as in the 15 embodiment heretofore described, the exception being that the units are of such shape and so disposed as that they are adaptable to a fire pot of rectangular form. In this form of the invention I make up the bed plate 20 of the end units 35 and side units 36 which are provided with depending flanges 37, up-standing ridges 38, and the edges of which abut at 39, and are preferably provided with undercut grooves 40 for fire clay to 25 prevent displacement. These units assembled as shown provide a rectangular base with a rectangular central opening in which is seated the oil pan 41 which has a downwardly turned rim flange 42 engaging the 30 upstanding rim 38 and having the centrally disposed boss 43 with the centrally placed perforated disk 44, through which loosely passes the oil feed pipe 45, said feed pipe being in turn surmounted by the distributer 35 plate 46, the pan 41 being provided with an overflow outlet 47 as shown.

The draft tubes 48 are similar in their general form to those heretofore described and are interlocked and detachably seated 40 in openings 49 in the end units 35 so as to have draft communication with the under side of the bed plate. The inner ends of the draft tubes 48 are nested as heretofore described, these inner ends being provided with 45 the walls 50 which serve to separate the ends of the draft tube from one another and direct the independent currents of air downwardly in a solid column upon the distributer 46.

In order that the device may be adjusted 50 for different widths and different lengths of fire pots within reasonable limits, I preferably provide extension plates 51 and 52, these plates being slotted as at 53 to receive suitable fastening devices, such as bolts 54, 55 by means of which they are secured to the side and end edges of the bed plate, the end plates 52 being cut away or shouldered as shown in Fig. 10, so as to give a flush-fit to the extension plate and insure tight corners.

60 From the foregoing it will be seen that I have provided a burner construction in which the bed-plate made up of units may be readily installed and said units, when assembled, are interlocked and held together

by the oil pan, which pan has connected 65 therewith in a readily detachable manner, the distributer and feed pipe, said units having associated therewith the knock-down draft tubes which can be quickly and conveniently installed or removed, so that the 70 entire structure may be conveniently placed and as conveniently dismantled.

The general operation of the burner is similar to burners of this type. The fuel oil of any desired or appropriate character 75 is fed to the distributer and ignited. Immediately the temperature of the distributer from this initial burning of the oil, becomes sufficient to vaporize the fuel oil, an oil gas is formed and this oil gas comingled with air 80 fed from the draft tubes, provides a fuel gas or vapor of high combustible qualities. The flame which results will, of course, impinge upon and heat the draft tubes so that the air currents, coming through said tube will be 85 preliminarily heated and delivered in such condition to the oil gas generated at the distributer plate, forming a fuel gas which will give a flame of high intensity and one which will be practically free from carbon or solid 90 products.

I claim:

1. In a device of the class described, the combination of a bed-plate; an oil distributer delivering above said bed-plate; 95 and a plurality of non-communicating draft tubes rising from said bed-plate and having their inner ends in closely nested relation and in contact with one another above said distributer, to deliver a body of air thereto in 100 independent, closely adjacent columns.

2. In a device of the class described, the combination of a bed-plate; an oil distributer delivering above said bed-plate; and a plurality of non-communicating draft 105 tubes removably mounted in said bed-plate and having their inner ends in closely nested relation and in contact with one another above said distributer, to deliver a body of air thereto in independent, closely adjacent 110 columns.

3. In a device of the class described, the combination of a bed-plate having draft-tube seats formed therein; an oil distributer delivering above said bed-plate; non-communicating draft-tubes detachably mounted in said bed-plate seats and having their inner ends in closely nested relation and in contact with one another above said distributer, to deliver a body of air thereto in independent, closely adjacent columns. 115

4. In a device of the class described, the combination of a bed-plate having draft-tube seats formed therein; an oil distributer delivering above said seats; and a plurality 120 of non-communicating draft-tubes having loose, interlocking engagement with said seats and free, closely nested ends in contact 125

with one another and delivering a body of air thereto in independent, closely adjacent columns.

5. In a device of the class described, a bed-plate formed of a plurality of independent units so disposed as to provide a central open area, some of said units having draft-tube seats formed therein; an oil pan having a centrally disposed boss loosely mounted on 10 said units over said central area; an oil-distributer loosely mounted in said pan boss; and a plurality of non-communicating draft-tubes loosely interlocked in said seats and having closely nested inner ends in contact 15 with one another and delivering a body of air in independent, closely adjacent columns to said distributer.

6. A bed-plate for oil burners formed of a plurality of independent segmental units so 20 disposed as to provide a central open area, one at least of said units having draft-tube seats formed therein.

7. A bed-plate for oil burners formed of a plurality of independent units so disposed as 25 to provide a central open area, an oil pan support at the inner edge of each of said units, and draft-tube openings having tube engaging supports formed in said units.

8. A bed-plate for oil burners formed of a 30 plurality of independent segmental units circularly disposed to provide a central open area, oil pan supporting ledges at the inner ends of said units, an oil pan loosely hung from said ledges and circularly disposed draft-tube openings having tube-engaging supports formed in said units.

9. In a device of the class described, the 35 combination of a bed-plate formed of a plurality of segmental units circularly disposed to provide a central, open pan-receiving area, and having draft-tube seats formed therein; an oil-pan suspended from the inner ends of said segments within said central area; a centrally disposed oil distributer delivering 45 above said pan; and a plurality of radially disposed non-communicating draft-tubes mounted in said seats and having converging, closely nested ends in supporting contact with one another to deliver a body of 50 air in independent, closely adjacent columns to said distributer.

10. An oil pan for burners having an upwardly projecting, centrally disposed hollow boss having an annular seat formed in the 55 top thereof; a perforated air plate loosely mounted in said annular slot and having a central oil pipe aperture; an oil pipe loosely traversing said air plate; a concavo-convex distributor disk having a depending boss provided with a through passage threaded 60 at its lower end and flaring outwardly at its upper end mounted on said oil pipe; and a loose supporting sleeve between said perforated plate and said disk to maintain the 65 distributor in proper relation to said boss.

11. In a device of the class described, the combination of a bed-plate having draft-tube seats therethrough, and draft-tubes having seat engaging ends provided with projecting supporting lugs detachably engaging 70 the under side of said bed plate.

12. In a device of the class described, a bed-plate having draft-tube seats therethrough and tube engaging ledges on the upper side of said bed-plate adjacent the 75 inner ends of said seats, and draft-tubes having seat engaging ends abutting said upstanding ledges at their inner portions and provided at their outer portions with supporting lugs engaging the under side of said 80 bed-plate.

13. In a device of the class described, a bed-plate having draft-tube seats therethrough and tube engaging ledges on the upper side of said bed-plate adjacent the 85 inner ends of said seats; and draft-tubes having seat engaging ends abutting said upstanding ledges at their inner portions and provided at their outer portions with supporting lugs engaging the under side of said 90 bed-plate, the inner projecting ends of said tubes being nested together.

14. In a device of the class described, the combination of a bed-plate made up of a plurality of units to permit the assembling or 95 disassembling of the bed-plate in a fire box through the furnace door, said units being so disposed as to give a central open area, and centrally disposed means for locking said units at their inner peripheries to maintain 100 them in proper position relative to one another.

15. In a device of the class described, the combination of a bed-plate made up of a plurality of units to permit the assembling or 105 disassembling of the bed-plate in a fire box through the furnace door, said units being so disposed as to leave a central open area, and a centrally disposed oil pan in said area, engaging said units so as to lock them in place 110 relative to one another.

16. In a device of the class described, the combination of a bed-plate made up of a plurality of units to permit the assembling or 115 disassembling of the bed-plate in a fire box through the furnace door, said units being so disposed as to provide a central open area, pan engaging elements on each of said units, and an oil pan in said central area, the edge of which engages said pan engaging 120 elements to lock the units in their assembled condition.

17. In a device of the class described, the combination of a bed-plate comprising a plurality of units to permit the assembling or 125 disassembling of the bed plate in a fire box through the furnace door, said units being so disposed as to form a central open area, pan engaging ribs at the inner ends of each of said units, an oil pan in said central area, 130

and rib engaging means at the edge of said pan to interlock with and hold said units in assembled position.

18. In a device of the class described, the combination of a bed-plate comprising a plurality of segmental units circularly disposed with respect to one another and providing a central open area, upstanding ribs

at the inner peripheries of said segmental units, an oil pan in said central area and a depending rib engaging rim at the periphery of said oil pan.

In testimony whereof I have hereunto set my hand.

WILLIAM D. MURRAY.
